FOREIGN PATENT DOCUMENTS

GB 4025455 7/2012

Primary Examiner — Holly Bayham*Assistant Examiner* — Rhea Shields(74) *Attorney, Agent, or Firm* — Gardner, Linn, Burkhardt & Flory, LLP(57) **CLAIM**

The ornamental design for a power center for a work surface, as shown and described.

DESCRIPTION

FIG. 1 is a top perspective view of a power center for a work surface showing our new design, shown in combination with a fastening collar;

FIG. 2 is another top perspective view of the power center for a work surface of FIG. 1, shown with the fastening collar engaged;

FIG. 3 is a top plan view of the power center for a work surface of FIG. 1;

FIG. 4 is a bottom plan view of the power center for a work surface of FIG. 1;

FIG. 5 is a front elevation of the power center for a work surface of FIG. 1;

FIG. 6 is a rear elevation of the power center for a work surface of FIG. 1;

FIG. 7 is a left side elevation of the power center for a work surface of FIG. 1; and,

FIG. 8 is a right side elevation of the power center for a work surface of FIG. 1.

In the drawings, the broken lines depict environmental subject matter only and form no part of the claimed design.
